UNITED STATES PATENT OFFICE

98,853

DESIGN FOR AN INSECT EXTERMINATOR

Claude E. Canning, Wilmette, Ill., assignor to
C. E. Canning, Incorporated, Chicago, Ill., a
corporation of Illinois

Application November 23, 1935, Serial No. 59,729

Term of patent 7 years

To all whom it may concern:

Be it known that I, Claude E. Canning, a citizen of the United States, residing at Wilmette, in the county of Cook and State of Illinois, have invented a new, original, and ornamental Design for an Insect Exterminator, of which the following is a specification, reference being had to the accompanying drawing, forming part thereof.

Figure 1 is a front elevational view of an insect exterminator embodying my new design.

Fig. 2 is an end view thereof.

My new design is characterized by an elongated base having upturned ends between which extends a cylindrical arrangement of insect exterminating elements, said base being supported by a centrally disposed pedestal.

I claim:

The ornamental design for an insect exterminator, substantially as shown and described.

CLAUDE E. CANNING.
